US00D889401S

(12) **United States Design Patent** (10) **Patent No.:** **US D889,401 S**
Li (45) **Date of Patent:** **** Jul. 7, 2020**

- (54) **USB PORTABLE POWER SUPPLY**
- (71) Applicant: **Yongjin Li**, Guangdong (CN)
- (72) Inventor: **Yongjin Li**, Guangdong (CN)
- (73) Assignee: **Shenzhen Lepower Electronic Co., Ltd.**, Shenzhen (CN)
- (**) Term: **15 Years**
- (21) Appl. No.: **29/667,670**
- (22) Filed: **Oct. 24, 2018**
- (51) LOC (12) Cl. **13-02**
- (52) U.S. Cl. **USPC D13/108; D13/103**
- (58) **Field of Classification Search**
USPC D13/103-110, 118, 119, 184, 199; D14/251, 253, 432, 434

Primary Examiner — Rosemary K Tarcza*Assistant Examiner* — Christy M Nemeth(57) **CLAIM**

The ornamental design for a USB portable power supply, as shown and described.

DESCRIPTION

FIG. 1 is a perspective view of a USB portable power supply showing my new design;

FIG. 2 is a front elevational view thereof;

FIG. 3 is a rear elevational view thereof;

FIG. 4 is a left side view thereof; and,

FIG. 5 is a right side view thereof.

1 Claim, 3 Drawing Sheets(56)
